ROPE TRAMWAY

Fredrik Johansen and Elmer J. Lloyd, Worcester,
Mass., assignors to The American Steel and
Wire Company of New Jersey, a corporation
of New Jersey

Application December 14, 1938, Serial No. 245,797

3 Claims. (Cl. 104—87)

This invention relates to improvements in rope tramways and more particularly to a connection adapted to permit the passage of a carrier for an aerial tramway from a rigid overhead rail to a suspended flexible track.

An object of this invention is to permit the passage of a tramway carrier from an overhead fixed rail onto a suspended track cable in a smooth and gradual manner.

10 A further object of this invention is to provide a curved bearing surface having a large radius so as to secure a maximum bearing surface of the movable rail end on the flexible cable.

These and other advantages will become apparent as the disclosure proceeds, in which:

Figure 1 is a side elevation of the movable rail end assembly;

Figure 2 is a section on line II—II of Figure 1;

Figure 3 is a section on line III—III of Figure 2;

Figure 4 is a section on line IV—IV of Figure 1; and,

Figure 5 is a section on line V—V of Figure 1.

In the drawing, the numeral 2 represents a cast steel movable rail end which is pivotally supported at 3 to the end of a rigid overhead rail or track 4. The rail end 2 is constructed to provide a main body portion of substantially inverted U-shaped cross-section, as shown in Figure 3, to form a carrier engaging surface 5. The end of the movable rail end 2, pivoted to the rigid overhead track 4, is extended beyond the main body portion to provide integral flange members 6 positioned on each side of the rigid overhead track and held in spaced relation to the end of the rigid overhead track by means of filler blocks 7. These filler blocks are suitably secured on each side of the rigid track independent of the pivotal connection between flanges

6 and the rigid track 4. The main body portion of the movable rail end 2 terminates in a flange 8 depending at a point substantially beyond the end of the rigid track 4. The flanges 6, which extend beyond the end of the movable rail end 2, are provided with curved surfaces 9 tapering downwardly toward the free end of the flanges and terminating at their free ends in a plane below the tread surface of the rigid track 4. The movable rail end is pivotally secured to the rigid track at a point above the plane of the flexible track 10 as clearly shown in Figure 1.

The opposite or free end of the movable rail end 2 is provided with upwardly extending flanges 12 which are in a plane below the plane of the flexible track 10, as clearly indicated in Figure 5.

In order to retain the free end in proper relationship to the flexible track 10, a filler block 14 is suitably secured between the flanges 12.

The movable rail end is provided, as shown in Figure 4, with a curved or arcuate-shaped bearing surface 15 which increases the bearing surface for the flexible track or cable 10 and decreases the bending stress in the wires of said flexible track cable. This curved bearing surface 15, in addition to providing a relatively large bearing surface for the flexible track or cable, is also curved transversely to align with the curvature of the various diameters of cable capable of being used for the flexible track 10. The radius of the bearing surface depends on the diameter 15 of the cable, size of wires and working tension.

Under such a construction, it is possible to permit a gradual transfer of the carrier 16 from the rigid track 4 to the flexible track 10. As the wheels 17, of the carrier 16, approach the end 2 of the rigid track 4, they engage, prior to the end of the track 4, the extended flanges 6 of the movable rail end 2, as shown in Figure 2 of the drawing. The top of these flanges 6 is curved to permit a gradual transfer of the carrier wheels 17 from the rigid overhead rail 4 onto the carrier engaging surfaces 5 of the movable rail end 2. The carrier being supported on the surface 5 of the rail end 2 passes over said rail end until it reaches a point substantially adjacent the free end thereof, whereupon it engages the extended flanges 12 prior to being transferred to the flexible track 10. The flanges 12 support the carrier wheels 17 until the tread portion of said wheels, due to the downward pressure caused by the weight of the carrier, engages the top of the flexible track 10, as shown in Figure 5. The weight of the carrier 16 then depresses the flexible track 10 to a slight degree and will continue to run on the flanges 12, due to their downward taper below the plane of the flexible member 10, until the resistance of the flexible track 10 is sufficient to support the load.

The flanges 12, of the movable end member 2, gradually taper downwardly toward their ends to a plane below the normal plane of the flexible track 10 and, due to this curvature, assist in the gradual transfer of the carrier 16 from the movable rail end 2 onto the flexible track 10. Therefore, the carrier 16 has been transferred from the rigid track 4 to the flexible track 10 in a smooth and gradual manner without any impact or jarring of the flexible track.

The wheels 17 of the carrier 16 transmit their load to the flexible cable 10 through the movable

rail end 2, such load being concentrated at the bearing surface 15. The flexible track 10, which deflects under the load, bends on the radius of the groove of the track cable deflecting saddle 18. 5 The flexible track also bends at the point of contact between the flexible track 10 and the large bearing surface 15, thus increasing the bearing surface for said flexible track and decreasing the bending stress in the wires forming the flexible track. Furthermore, as the load is applied to the flexible track, the curved bearing surface 15 slides a short distance on said flexible track and when the load is removed, the flexible track resumes its position and the large curved bearing surface 15 slides in the opposite direction on the flexible track. This slow intermittent sliding action tends to wear both the wires of the cable forming the flexible track and the movable rail end but due to the long radius bearing surface 15 of the movable rail end, the unit of bearing pressure is small and wear of the flexible track and movable rail end is minimized. 10 15 20 25 30 35 40 45 50 55 60

Such a smooth transfer of the carrier from the rigid track to the flexible track overcomes the main difficulties experienced in overhead transfer devices now in use. It eliminates continual pounding of the wires forming the flexible track and lessens the danger of a rupture to the wire constituting the flexible track.

While we have shown and described a specific embodiment of our invention, it will be understood that we do not wish to be limited exactly thereto, since various modifications may be made without departing from the scope of the invention, as defined by the following claims.

We claim:

1. In an overhead track construction including a rigid track and a flexible track, a movable rail having a substantially inverted U-shaped construction pivotally supported by said rigid track and interposed between said rigid track and flexible track comprising a main body portion, said main body portion including a longitudinally extending arcuate-shaped bearing surface formed on one end thereof which rests upon said flexible track, said arcuate-shaped bearing surface having a relatively large radius of curvature whereby the radius of the catenary formed by the flexible track when the same is loaded decreases and approaches the radius of curvature of the arcuate-shaped bearing surface so that the amount of bearing surface of the movable rail in contact with the flexible track increases as the load thereon increases, and flanges on each end of said main body portion, said flanges on one end disposed on each side of said rigid track and the flanges on the other end disposed on each side of said flexible track, the top surface of said flanges approaching gradually to the level of the tread surfaces of the respective tracks so that a carrier is transferred from said rigid track to said flexible track in a smooth and

gradual manner and with no impact on the flexible track.

2. In combination with a rigid track and a flexible track, a movable rail end pivotally supported by said rigid track above the horizontal plane of the flexible track, said movable rail end comprising a main body portion of substantially inverted U-shaped cross section having a longitudinally extending arcuate-shaped engaging surface which rests upon said flexible member, integral flanges extending from each end of said main body portion and disposed on each side of said rigid track and flexible track, said arcuate-shaped engaging surface having a relatively large radius of curvature which is arranged thereon between the flanges on the outer end of the main body portion whereby the radius of curvature of the catenary formed by the flexible track when loaded decreases and approaches the radius of curvature of the arcuate-shaped engaging surface so that the amount of bearing surface of the movable rail end in contact with said flexible track increases as the load thereon increases, said bearing surface curved transversely to conform to the diameter of the flexible track, the flanges on both ends of said main body portion having curved faces to conform with the respective tracks, to the contour of a wheel carrier, the top surfaces of said flanges approaching gradually to the level of the tread surface of the respective tracks so that a carrier is transferred from said rigid track to said flexible track in a smooth and gradual manner devoid of any pounding to said flexible track. 10 15 20 25 30 35 40 45 50 55 60

3. The combination with a rigid track and a flexible cable track cooperating therewith, of a movable rail member interposed between the rigid track and the flexible cable track, said movable member having the inner end thereof pivotally connected to said rigid track above the horizontal plane of the flexible track with the opposite outer end thereof having a longitudinally extending arcuate-shaped bearing surface arranged therewith which rests upon the flexible cable track, the outer end of said movable rail member disposed on said flexible track having substantially an inverted U-shaped cross-section with the arcuate-shaped bearing surface arranged therewith having a relatively large radius of curvature and extending throughout a substantial part of the outer end portion of the rail member which overlies the flexible track whereby the radius of curvature of the catenary formed by the flexible track when the same is loaded decreases and approaches the radius of curvature of the arcuate-shaped bearing surface so that the amount of bearing surface of the outer end of the movable rail member in contact with said flexible track increases as the load thereon increases. 60 65 70 75 80 85 90 95
